Primary Examiner — Zenia I Bennett*(74) Attorney, Agent, or Firm* — Bereskin & Parr
LLP/S.E.N.C.R.L, s.r.l.; Isis E. Caulder; Ahmed Elmallah(57) **CLAIM**

The ornamental design for a light fixture, as shown and described.

DESCRIPTION

FIG. 1 shows a top right perspective view of the light fixture. FIG. 2 shows a top left perspective view of the design of FIG. 1.

FIG. 3 shows a front side elevation view of the design of FIG. 1.

FIG. 4 shows a right side elevation view of the design of FIG. 1.

FIG. 5 shows a rear side elevation view of the design of FIG. 1.

FIG. 6 shows a left side elevation view of the design of FIG. 1.

FIG. 7 shows a top plan view of the design of FIG. 1; and, FIG. 8 shows a bottom plan view of the design of FIG. 1.
